UNITED STATES PATENT OFFICE

ROMAIN DE BERSAQUES, OF WASHINGTON, DISTRICT OF COLUMBIA.

CORKSCREW.

No. 927,127.

Specification of Letters Patent.

Patented July 6, 1909.

Application filed April 26, 1909. Serial No. 492,398.

To all whom it may concern:

Be it known that I, ROMAIN DE BERSAQUES, a subject of the King of Belgium, residing at Washington, District of Columbia, have invented certain new and useful Improvements in Corkscrews; and I do hereby declare the following to be a full, clear, and exact description of the invention, such as will enable others skilled in the art to 10 which it appertains to make and use the same, reference being had to the accompanying drawings, and to the letters of reference marked thereon, which form a part of this specification.

15 This invention relates to new and useful improvements in cork screws and comprises various details of construction and combinations and arrangements of parts which will be hereinafter fully described and then specifically defined in the appended claims.

20 My invention is illustrated in the accompanying drawings, in which:—

Figure 1 is a perspective view showing the application of my invention to the neck 25 of a bottle. Fig. 2 is a sectional view transversely through the threaded shank portion of the screw showing parts in top plan view. Fig. 3 is a sectional view on line 3—3 of 30 Fig. 1. Fig. 4 is a vertical sectional view centrally through the swivel member through which the threaded shank of the device passes, parts being shown in elevation, and Fig. 5 is a detail perspective view of the handle.

35 Reference now being had to the details of the drawings by characters, A designates a disk having the integral arms A' projecting therefrom which terminate in a ring B at their lower ends which are adapted to rest 40 upon the upper end of the neck of a bottle in the manner shown in Fig. 1 of the drawings. Said disk A is provided with a central aperture in which the swiveled member D is mounted, which has a ring D' fixed 45 about its circumference at the lower end thereof and the circumference of the upper portion of said swiveled member is provided with gear teeth E and projecting from the inner circumference of the opening in said member are the lugs F. H designates a shaft having a spiral groove H' therein and which passes through the member D, the lugs F thereon engaging said spiral groove H', and which member and screw normally turn 50 together excepting during the act of extracting the stopper. Projecting from the upper

edge of said disk is a lug N which is apertured for the reception of a pin O, and O' designates a spring which bears between the head of said pin and said lug and tends to normally hold the inner end of the pin out of engagement with the teeth E upon the member D. Said disk is provided with a slot R through which a longitudinally movable pin actuating bar T passes, said bar 60 having a handle T' pivoted to its lower end. The upper end of the bar T has a cam projection S which is adapted, as the bar is moved downward by depressing upon the handle T', to bear against and move the pin 65 against the tension of the spring so that the inner end of the pin will engage one of the teeth E and cause the same to be held stationary. One of the flanges A' is provided with a longitudinal slot a through which the 70 shank portion of said handle T' passes and in which a portion of the bar T has a longitudinal movement. A pin L, which forms a pivotal connection between the bar T and the handle T', extends beyond the edges of 75 the slot and bears against the rear of the slotted standard A' and serves to hold the bar from drawing through the slot a.

Projecting from the bottom of the shaft H is a cork screw which turns with said 80 shaft. A handle W is fastened to the upper end of the shaft H and has its ends formed one with a slot W' and the other recessed away as at W² and forming convenient means for removing corks of bottles, etc.

85 In operation, the apparatus is applied to the top of a bottle in the manner shown in Fig. 1 and, by turning the handle, the cork screw may be turned into the stopper in the usual manner. When it is desired to withdraw the stopper, the operator by pressing upon the handle T' will cause the bar T to 90 be drawn downward and push the pin into engagement with one of the teeth of the swivel member D, thus holding the latter 95 stationary and, upon a further turning of the handle D with the member D held stationary, an outer longitudinal movement will be imparted to the shaft H, causing the stopper to be withdrawn from the bottle. When 100 the pin is at its farthest inner throw and engaging one of the gear teeth E, the head of the pin will be in contact with the cam edge 105 of the bar and, when pressure is released from the handle connected to the bar, the 110 pin bearing under the influence of the spring against said cam edge will cause said bar to

be moved slightly longitudinally to its normal position.

What I claim to be new is:—

1. A cork screw comprising a disk and a ring with connections between the same, a hollow swiveled member mounted in an aperture in said disk, teeth about the circumference of said member, lugs projecting from the bore of said member, a shaft passing through said member and provided with a spiral groove engaged by said lugs, a handle upon said shaft, a cork screw projecting from the end of said shaft, a spring-pressed pin mounted upon the disk and normally out of engagement with said teeth, a longitudinally movable bar having a lateral projection adapted to bear against said pin to throw the latter into engagement with one of the teeth of said member to hold the same stationary, and a handle for moving said bar longitudinally.

2. A cork screw comprising a disk and a ring, standards connecting said disk and ring, one of said standards being slotted, a hollow swiveled member mounted in an aperture in said disk, teeth about the circumference of said member, lugs projecting from the bore of said member, a shaft passing through said member and provided with a spiral groove engaged by said lugs, a handle upon said shaft, a cork screw projecting from the end of said shaft, a spring-pressed pin mounted upon the disk and normally out of engagement with said teeth, a longitudinally movable bar having a lateral projection adapted to bear against said pin to throw the latter into engagement with one of the teeth of said member to hold the same stationary, a longitudinally movable bar passing through a slot in said disk and having a cam projection adapted to bear against said pin to throw the latter into engagement with one of the teeth of said member to hold the same stationary, a longitudinally movable bar passing through a slot in said disk and having a cam projection adapted to bear against said pin to throw the latter into engagement with one of the teeth of said mem-

ber to hold the same stationary, a handle pivoted to said bar and passing through a slot in one of the standards between said disk and ring.

3. A cork screw comprising a disk and a ring, standards connecting said disk and ring, one of said standards being slotted, a hollow swiveled member mounted in an aperture in said disk, teeth about the circumference of said member, lugs projecting from the bore of said member, a shaft passing through said member and provided with a spiral groove engaged by said lugs, a handle upon said shaft, a cork screw projecting from the end of said shaft, a spring-pressed pin mounted upon the disk and normally out of engagement with said teeth, a longitudinally movable bar having a lateral projection adapted to bear against said pin to throw the latter into engagement with one of the teeth of said member to hold the same stationary, a longitudinally movable bar passing through a slot in said disk and having a cam projection adapted to bear against said pin to throw the latter into engagement with one of the teeth of said member to hold the same stationary, a pin fastened to said bar and projecting beyond the opposite sides thereof, a handle extending through the slot of the standard and pivotally mounted upon said pin, the ends of said pin upon the bar adapted to bear against the inner edge of the slotted standard for preventing the bar moving through the slot in the standard.

In testimony, whereof I have signed my name to this specification in the presence of two subscribing witnesses this 23 day of April nineteen hundred and nine.

ROMAIN DE BERSAQUES.
